UNITED STATES PATENT OFFICE.

RALPH J. HALL, OF FALLS CITY, OREGON.

TIE-SLIDE FOR COLLARS.

1,277,310.

Specification of Letters Patent. Patented Aug. 27, 1918.

Application filed August 27, 1915. Serial No. 47,682.

To all whom it may concern:

Be it known that I, RALPH J. HALL, a citizen of the United States, residing at Falls City, in the county of Polk and State 5 of Oregon, have invented certain new and useful Improvements in Tie-Slides for Collars; and I do hereby declare the following to be a full, clear, and exact description of the invention, such as will enable others 10 skilled in the art to which it appertains to make and use the same.

This invention relates to tie slides for collars and the principal object of the invention is to provide a device adapted to prevent 15 a necktie from sticking when the same is being adjusted in a fold collar.

Another object of the invention is to provide a device which may be readily attached to collars of the ordinary type or which may 20 be at the time of manufacture secured within the collar, thus insuring the same at all times being in operative position.

Still another object of the invention is to provide a spacer which will hold the outer 25 fold from the inner fold of the ordinary type of collar thereby allowing space through which the tie may be easily slipped.

With these and other objects in view, the invention consists in the novel combination 30 and arrangement of parts which will be fully set forth in the following specification and accompanying drawings, in which:—

Figure 1 is a view illustrating my improved collar having a tie slide formed there- 35 in at the time the collar is made.

Fig. 2 is an enlarged sectional view on line 2—2 of Fig. 1.

Fig. 3 is a fragmentary view of the device used as an attachment to a collar, and 40 Fig. 4 is a sectional view on line 4—4 of Fig. 3.

Referring to the drawing, the numeral 1 indicates a turned down collar of the usual type now in general use. The collar com- 45 prises an outer fold 2 and an inner fold 3, which folds have secured thereto on the inner side a reinforcing ply 4. A ply 5 is secured to the ply 4 carried by the inner fold 3 and has its top and bottom edges terminat- 50 ing flush with the crease 6 of the collar and the lower edge of the inner fold. The inner fold has formed at each end a locking tab 7 which has the usual button holes 8 there-

in. The ply 5 is provided adjacent its upper and lower edges with longitudinally extending 55 out-struck ridges 9, which ridges have their ends terminating adjacent the vertical edges of the outer fold 2 so that when the collar is ready for use, the said ridges will be located between the folds and entirely hidden 60 from the exterior view. The plies 3, 4 and 5 are the usual plies of a collar.

A suitable filler 10 is positioned within the ridges 9 so as to prevent them from collapsing and to urge the ridges into engagement 65 with the inner face of the ply 4 carried by the outer fold 2, thus providing a sufficient tie space between the folds 2 and 3 and the plies carried thereby. The lower ridge also prevents a tie from slipping down below the 70 bottom edges of the folds after the tie has been positioned between the folds and plies.

Referring to the modified form illustrated in Figs. 3 and 4, there it is shown a turned down collar having an outer fold 11 and an 75 inner fold 12. A reinforcing ply 13 is secured to the inner sides of the folds 11 and 12 as clearly illustrated in the figures mentioned.

A reinforcing strip 14 is secured to the ply 13 carried by the inner fold 12 and the strip has its upper and lower edges secured in any suitable manner to the ply 13, it being understood that this strip does not extend over the entire surface of the ply 13. The 80 strip 14 is provided adjacent its upper and lower longitudinal edges with outstanding ridges 15, in which is secured a suitable filler 16 for preventing the ridges from collapsing and at the same time forcing the ridges 90 into engagement with the ply carried by the outer fold so as to provide a tie receiving space, whereby a tie may freely slide between the folds and be prevented from slipping down below the bottom edges thereof. 95

It will be apparent that this construction permits the collar to be manufactured at a comparatively small expense.

What is claimed is:—

A turned down collar including an inner 100 and outer fold having a reinforcing ply se- cured to the inner side thereof, a second ply secured to the ply carried by the inner fold of the collar, said second ply provided ad- jacent its upper and lower edges with out- 105 standing ridges, a filler secured in the ridges

to prevent the latter from collapsing and to urge the ridges into engagement with the
ply carried by the outer fold, said ridges
providing a tie space between the folds and
5 preventing a tie from slipping below the
bottom edges of the folds.

In testimony whereof I affix my signature
in presence of two witnesses.

RALPH J. HALL.
